Nelson W. Howard

UNITED STATES PATENT OFFICE.

EDWARD ERICKSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

APPLYING APPARATUS.

Application filed August 3, 1922. Serial No. 579,443.

- The present invention relates to apparatus for the application of fluids to shoe-parts, and especially that for blacking or staining the edges of soles.
- 5 Objects of my invention are to provide such an apparatus by which the application of the stain or other fluid may be made rapidly, uniformly and without waste.
- In the attainment of these objects, as a 10 feature of the invention, I combine with an applying member means movable into and out of co-operation with it for delivering the fluid to be applied, and means governed by the work for controlling the delivery of the fluid.
- 15 By this, as an incident to an act performed by the operator for another purpose and without giving consideration to the controlling effect, the delivery to the applying member may be made only at the times or in 20 the quantities desired. As herein illustrated, a delivering member travels in a stain-receptacle and the amount of stain delivered to the applying member, the latter preferably being a rotatable brush, may be governed by 25 moving the delivering member toward and from the brush, as by a movement of the receptacle. I prefer to effect the controlling movement of the delivering member through its connection to a movable work-gage. In 30 addition to the movement through which it exercises control of the delivering member, the normal position of the gage may be varied, and, as illustrated, there is a capacity for adjustment in a plurality of directions.
- 35 One of these adjustments may be in the direction of the controlling movement, adapting the apparatus for operation upon shoes having different degrees of sole-extension, while another adjustment may be toward and 40 from the brush, altering the width of the sole-edge over which said brush operates. This last adjustment permits the edges of white-stitched soles to be stained without soiling such stitching.
- 45 As another feature of the invention, there is provided an applying member rotatable about an inclined axis and having a conical applying surface. At its lowermost portion, this surface is substantially horizontal, to 50 adapt it to act upon the work, while with the opposite approximately vertical side co-operates means for delivering a coating fluid at a point spaced a substantial distance from the point of application of the work and out of the range of movement of the latter. As 55 illustrated, the applying member is in the form of a brush, and co-operating with this brush is a work-gage, movable in a plane substantially at right angles to the applying surface. Preferably, the brush has a conical 60 head, along which the gage moves. The brush is shown as rotatable about an inclined axis, the applying surface being approximately horizontal. The gage is adjacent to an edge of the horizontal side, and fluid-delivering means is associated with the opposite side. With this arrangement, all 65 portions of the work operated upon may be coated properly, without interference between the upper and the gage, and it also facilitates the delivery of fluid to the brush. Then, too, the work may be presented to the applying member in a natural manner, tending to rapidity and accuracy of operation. 70 The brush-surface to which the delivery is 75 made is shown as vertical, the delivering member being thereby readily arranged to travel over it.
- These and other features of the invention are illustrated in the accompanying drawing showing one embodiment of my improved applying apparatus in elevation.
- Carried at the outer extremity of a generally horizontally extending arm 10 of a frame 12 is a support 14 for the applying 80 member 16. To provide for the correct initial positioning of the applying member with reference to its associated elements, it may be adjustably mounted upon the frame-arm, as by bolts 18 passing through the 85 frame and also through vertical slots 20 in the support 14. The downward limit of this adjustment may be more exactly determined by a screw 22 threaded through the support in a boss above one of the slots 90 and having its lower extremity arranged to contact with the corresponding bolt 18. A check-nut 24 serves to retain the screw 22 in the position to which it is adjusted. Preferably, the applying member is in the form 100 of a brush consisting of a head or supporting body 26, from which may project a ring of fibers 28. The brush is fixed upon a spindle 30 journaled in an inclined position in the support 14, the inclination of this spindle being downwardly and inwardly toward 105

the frame, and being shown as lying at an angle of substantially 45 degrees to the horizontal. Both the periphery of the brush-body and the applying surface 32 are conical, being approximately frusta of cones placed base to base. The brush-spindle is rotatable through bevel-gearing 34 from a vertical sectional shaft 36, the portions of which are united for longitudinal movement to allow the brush-adjustment just described. This shaft 36 is journaled in the frame-arm, and is driven by worm-gearing 38 from a horizontal shaft 40 rotatable in the top of the frame and shown as connected directly to the shaft of a motor 42.

Below and at the inner side of the brush 16 is a stain-receptacle 44 mounted to tilt about a stud 46 fixed in a horizontal position to the side of the frame, and passing through a passage which may be cast integrally with the opposite walls of the receptacle. This receptacle is held upon the stud, for ready removal and replacement to permit its cleaning, by a washer 48 having a keyhole-slot 50 co-operating with opposite slots in the sides of the outer extremity of the stud 46. The bottom of the receptacle is curved, and at one side the upper portion is horizontal, as is indicated at 52, giving an opening convenient for the introduction of the staining fluid, while the opposite side of the receptacle has an upward extension 54, which at its top lies below the inner vertical edge of the brush. Rotatable about a spindle 56 carried by the extension 54 of the receptacle is a sprocket-wheel 58, and over this and a small sprocket-wheel 60, rotatable upon an arm 61 fixed to the stud 46, passes an endless stain-delivering member furnished by a chain 62. The arm 61 is preferably angularly adjustable about the stud to give the desired tension to the chain, it being fixed in position by a screw 63 drawing together the sections of its divided hub. This chain is so located that it may travel counter-clockwise, as is indicated by the arrow applied to its outer run, so that one side will move from a point near the bottom of the receptacle upwardly into proximity to or contact with the upper, inner side of the brush 16 at a point removed a substantial distance from the point of application of the work so that there is room for manipulation of the latter. The travel of the chain is produced by a pulley 64 turning about the spindle 46 between the receptacle 44 and the frame, and receiving power through a belt 66 passing over guide-pulleys 68, 68 rotatable at the upper portion of the frame, and then over a pulley 70 fast upon the upper extremity of the sectional shaft 36. Connected to or formed integrally with the pulley 64 is a sprocket-wheel 72, joined by a chain 74 to a sprocket-wheel 76 secured to turn with the sprocket-wheel 58.

The chain 62 is held normally out of contact with the brush to prevent the delivery of stain to the latter when no work is in position to be operated upon. The accomplish this, the spindle 56 has, encircling its end, a rod 78 guided in an opening in a bracket 80 projecting from the side of the frame-arm 10. Movement of this rod is allowed to an adjustable extent in either direction by pairs of nuts and lock-nuts 82, 82 and 84, 84, respectively above and below the bracket 80. Near the lower end of the rod is fixed a collar 86, and above this, encircling the rod and resting upon the collar is a helical spring 88 supporting a sliding flanged collar 90. Extending between the flanges of the collar 90 is one arm of a bell-crank-lever 92 fulcrumed upon the frame-arm and having its opposite extremity connected by a link 94 to a lever 96 fulcrumed at its lower end upon the frame near the top of the receptacle. This lever 96 extends upwardly and outwardly to a point above the brush, and has an angular end-portion 98, which is substantially vertical and reaches a point outside the brush. The portion 98 is adjustable laterally toward and from the brush by being pivoted at 100 to the body 96 of the lever, it being fixed in its adjusted relation by a screw 102 threaded into the lever and passing through an arcuate slot 104 in the portion 98. At the bottom of this lever-portion is a divided socket to receive the shank 106 of a gage-support 108. A screw 110 serves to draw the sides of the socket together to clamp the gage-support in place. Mounted to turn upon the support 108 is a gage-disk 112, the axis of rotation of which is substantially horizontal. The inner side of this disk is concave, so that the periphery of the brush may enter it and permit close proximity between these elements. It is to be noted that the head of the brush at this point and the immediately adjacent portion of the fibers are approximately vertical, so that the entry of the brush into the disk-concavity is facilitated. The gage-disk is designed for engagement with the crease of a shoe to be operated upon, and to prevent the edge of the disk from entering too deeply into the crease and thus resisting the movement of the work over it, it is rounded, and the outer face 114 of the disk diverges rather abruptly from the periphery, giving a considerable thickness of material for contact with the upper face of the sole or of the welt at one side, and the material of the shoe-upper upon the other. Normally, the weight of the lever 96 and associated parts, aided by a spring 111 interposed between the lever and frame, holds the gage-disk 112 in its lowest position, and this, acting through the link 94 and the bell-crank-lever 92, urges the sliding collar 90

against the nuts 82, raising these until they are stopped by the bracket 80, thus removing the chain 62 from contact with the brush by swinging the receptacle 44 about its stud 46. Therefore, though the elevation of the stain by the chain from the receptacle is continuous, it is not delivered to the brush under these conditions. When the operator applies a shoe S to the gage-disk 112 and presses it upwardly, this disk, raised by its engagement with the crease swings the lever 96 about its fulcrum, and through the link 94 turns the bell-crank-lever 92 in a clockwise direction. The pressure of the lower end of this lever upon the sleeve 90 transmits the movement through the spring 88 to the rod 78, tilting the receptacle 44 about the stud 46 and bringing the chain 62 into yielding contact with the brush at a position upon the vertical face of the brush which is above the receptacle so that any drippings are caught thereby. Consequently, when the sole-edge reaches the lower portion of the brush, stain is being delivered by the chain to the upper portion, at a point out of the range of movement of the work and spaced a substantial distance from the point of application of the work. Thus the brush in its rotation, as indicated by the arrow, spreads such stain upon the edge of the sole. This application is in the direction of extension of the periphery, so there is no tendency to throw the stain toward the upper, which is also protected by the gage, or to overrun upon the sole. It should be observed that the inclination of the spindle 30 and that of the applying surface of the brush are such as to cause the latter at its lowermost portion to be substantially horizontal, while the adjacent face of the gage-disk at its periphery is approximately at right angles to this and its axis of rotation parallel thereto. This places the applying surface in such a position that the operator may most easily hold and present the shoe to it. The shoe-sole is now rotated, under the guidance of the gage, until the entire sole-edge has been brought into contact with the brush. When the shank-portion is reached, the work may be tilted to keep the applying surface in the proper transverse relation thereto, without interference between the upper and gage-disk. The staining of the edge having been completed, the operator disengages the work from the gage-disk, which falls, moving the chain 62 away from the brush and stopping the feed of stain. According to the amount which the edge of the sole projects with relation to the upper, the support 108 may be adjusted vertically in its socket, or in the same direction as the movement which controls the stain-delivery, so that the co-operation between the work and brush may be effected with minimum effort. If the sole is attached to the welt by

white stitching and it is desired that this shall be kept free of stain, the portion 98 of the lever 96 may be adjusted upon its pivotal connection to so position the gage-disk with relation to the adjacent side of the brush that the latter does not fully coat the sole-edge, but leaves a very slight untreated margin. This insures against the flow of the ink over the edge of the welt to the stitching. The side of the brush opposite the lower applying area is nearly vertical, and this lends itself admirably to the co-operation with it of the stain-delivering chain, without interfering with the movement of the work during the operation. Moreover, the receptacle may readily be carried beneath this portion of the brush to present the chain to it and to receive the drip of the stain.

Having described my invention, what I claim as new and desire to secure by Letters Patent of the United States is:

1. In an applying apparatus, an applying member, means movable into and out of co-operation with the applying member to deliver fluid thereto, and means governed by the work for controlling such delivery.

2. In an applying apparatus, an applying member, means movable into and out of contact with the applying member to deliver fluid thereto, means for controlling such movement, and means arranged to vary the extent of such movement.

3. In an applying apparatus, an applying member, means movable into and out of contact with the applying member to deliver fluid thereto, and means governed by the work for controlling such movement.

4. In an applying apparatus, an applying member, a source of fluid, a movable delivering member, means for moving the delivering member between the source and the applying member, and means governed by the work for moving the delivering member into and out of co-operation with the applying member.

5. In an applying apparatus, an applying member, a source of fluid, an endless member, supports adjacent respectively to said source and to the applying member and over which the endless member travels, means for causing such travel, and means for controlling the delivery of fluid by the member.

6. In an applying apparatus, an applying member, a source of fluid, an endless delivering member, supports adjacent respectively to said source and to the applying member and over which the endless member travels, means for causing such travel, and means for moving one of the supports to carry the delivering member into and out of contact with the applying member.

7. In an edge-staining apparatus, a rotatable brush, a stain-receptacle, a stain-delivering member arranged to travel between the receptacle and brush, means for causing such

- travel, and means operating as an incident to an act performed upon the work for varying the amount of stain delivered by the member.
5. 8. In an edge-staining apparatus, a rotatable brush, a stain-receptacle, a chain arranged to travel between the receptacle and brush, and means for moving the chain into and out of contact with the brush.
10. 9. In an edge-staining apparatus, a rotatable brush, a stain-receptacle, a chain arranged to travel in the receptacle, and means for moving the receptacle to carry the chain toward and from the brush.
15. 10. In an edge-staining apparatus, an applying member, a movable work-gage co-operating therewith, means movable into contact with the applying member for delivering stain thereto, and connections to the gage arranged to control the delivery of stain to the applying member.
20. 11. In an edge-staining apparatus, a rotatable applying member, a movable work-gage co-operating therewith, movable means for delivering stain to the applying member, and connections between the gage and delivering means to communicate movement from one to the other.
25. 12. In an edge-staining apparatus, a rotatable applying member, a movable work-gage co-operating therewith, movable means for delivering stain to the applying member, means for moving the delivering means between the receptacle and applying member, and connections between the gage and delivering means arranged to move said delivering means toward and from the applying member.
30. 13. In an edge-staining apparatus, a rotatable brush, a movable crease-gage co-operating therewith, means for supplying stain to the brush, and supply-controlling means connected with the crease-gage.
35. 14. In an edge-staining apparatus, a rotatable brush, a movable crease-gage co-operating therewith, a stain-receptacle, a stain-delivering member traveling between the receptacle and brush and being independently movable toward and from the brush, and connections between the crease-gage and stain-delivering member.
40. 15. In an edge-staining apparatus, a rotatable brush, a crease-gage movable under the influence of the work, a movable stain-receptacle, a chain traveling in the receptacle to deliver stain to the brush, and connections between the crease-gage and receptacle.
45. 16. In an applying apparatus, an applying member, means for delivering fluid thereto, a gage co-operating with the work and movable independently of the applying member to control the delivery of fluid, and means arranged to vary the normal position of the gage.
50. 17. In an applying apparatus, an applying member, means for delivering fluid thereto, a gage co-operating with the work and movable to control the delivery of fluid, and means arranged to vary the normal position of the gage in a plurality of directions with respect to the applying member. 70
55. 18. In an applying apparatus, an applying member, means for delivering fluid thereto, a gage co-operating with the work and movable to control the delivery of fluid, and means arranged to vary the normal position of the gage in the direction of its controlling movement. 75
60. 19. In an applying apparatus, an applying member, means for delivering fluid thereto, a gage co-operating with the work and movable independently of the applying member to control the delivery of fluid, and means arranged to vary the normal position of the gage toward and from the applying member. 80
65. 20. In an edge-staining apparatus, a rotatable brush, a stain-receptacle, means for controlling the delivery of stain from the receptacle to the brush, a movable work-gage, connections between the gage and delivery-controlling means, and means arranged to vary the relation of the gage to the brush and to the connections. 90
70. 21. In an edge-staining apparatus, a rotatable brush, a stain-receptacle, a stain-delivering member traveling in the receptacle and being mounted for movement toward and from the brush, a work-gage co-operating with the brush, a movable support for the gage, means arranged to permit the adjustment of the position of the gage upon the support, and connections between the support and stain-delivering member. 100
75. 22. In a sole-edge-staining apparatus, a movable brush having a conical applying surface, and a work-gage movable in a plane substantially at right angles to the applying surface. 110
80. 23. In a sole-edge-staining apparatus, a brush having a conical head and conical applying surface, such conical portions being oppositely inclined, and a work-gage situated adjacent to one edge of the applying surface and being movable along the conical portion of the head. 115
85. 24. In a sole-edge-staining apparatus, a movable brush having an applying surface, a lever, and a work-gage mounted upon the lever and being movable substantially at right angles to the applying surface in the movement of the lever upon its fulcrum. 120
90. 25. In a sole-edge-staining apparatus, a movable brush having an applying surface, a lever having an arm extending toward the applying surface, and a gage-disk rotatable upon the arm about an axis substantially parallel to the applying surface. 125
95. 26. In a sole-edge-staining apparatus, a 130

movable brush having a conical applying surface, a lever having an arm extending toward the applying surface, and a gage-disk rotatable upon the arm adjacent to the applying surface, said disk in the movement of the lever upon its fulcrum being movable in a plane substantially at right angles to the applying surface.

27. In a fluid-applying apparatus, a brush 10 rotatable about an inclined axis and provided with a conical applying surface having its lowermost portion substantially horizontal, a work-gage co-operating with such horizontal portion, and means for delivering fluid to the opposite portion of the applying surface.

28. In a fluid-applying apparatus, a brush 20 rotatable about an inclined axis and provided with a conical applying surface having its lowermost portion substantially horizontal, and its uppermost portion substantially vertical, a work-gage situated at an edge of such horizontal portion, and means for delivering fluid to the vertical portion.

29. In a fluid-applying apparatus, a brush 25 rotatable about an inclined axis and provided with a conical applying surface having its lowermost portion substantially horizontal and its uppermost portion substantially vertical, a work-gage situated at an edge of such horizontal portion, a fluid receptacle extending beneath the vertical portion, and a fluid-delivering member movable in the receptacle and contacting with the brush.

30. In a fluid-applying apparatus, a brush 30 rotatable about an inclined axis and provided with a conical applying surface having its lowermost portion substantially horizontal and its uppermost portion substantially vertical, a work-gage situated at an edge of such horizontal portion, a fluid-receptacle extending beneath the brush and a chain traveling through the fluid in the receptacle and contacting with the vertical portion of 45 the brush.

31. In a sole-edge-staining apparatus, a brush 40 rotatable about an inclined axis and provided with oppositely inclined conical applying and supporting portions, the applying surface extending substantially horizontally for contact with a sole-edge, and a work-gage co-operating with such horizontal applying surface and extending in proximity to the adjacent supporting portion.

32. In a sole-edge-staining apparatus, a brush 50 rotatable about an inclined axis and provided with oppositely inclined conical applying and supporting portions, the applying surface extending substantially horizontally for contact with a sole-edge, and a work-gage co-operating with such horizontal applying surface and having a concavity to receive the supporting portion.

33. In a sole-edge-staining apparatus, a rotatable stain-applying brush, a crease-gage 65 movable along the brush under the influence of the work, and means arranged to vary the distance between the brush and movable crease-gage and thereby the distance between the upper edge of the sole and the adjacent edge of the brush.

34. In a fluid-applying apparatus, an applying member rotatable about an inclined axis and provided with a conical applying surface having the lowermost portion of the 75 surface substantially horizontal, and means for delivering fluid to the conical applying surface of the applying member at a point substantially diametrically opposite said horizontal portion.

35. In a fluid-applying apparatus, an applying member provided with a conical applying surface rotatable about an axis inclined to the horizontal, and having the lowermost portion of its applying surface exposed for contact with a piece of work, and means for delivering fluid externally to another point upon the conical applying surface above the point of application of the work and out of the range of movement of the work.

36. In a fluid-applying apparatus, an applying member rotatable about an inclined axis and having an applying surface which is the frustum of a cone the apex of which 95 is directed downwardly, said applying member having the lowermost portion of its applying surface exposed for the application of work, a fluid receptacle disposed at one side of the path of movement of work being presented to the applying member, and means for elevating fluid from the receptacle and delivering it to the face of said applying member at a point removed a substantial distance from the point of application of the 100 work.

37. In a fluid-applying apparatus, an applying member rotatable about an inclined axis and provided with a conical applying surface the lowermost portion of which approximates a horizontal position and the uppermost portion of the surface of which approximates a vertical position, the lower portion of said applying device being exposed for the application of work thereto, a 110 fluid receptacle disposed laterally of the point of application of the work and extending beneath the substantially vertical portion of the surface of said applying member, and means for elevating fluid from said 115 receptacle and applying it to said vertical portion.

In testimony whereof I have signed my name to this specification.

EDWARD ERICKSON.
